UNITED STATES PATENT OFFICE.

JOHN T. CARTER, OF BALTIMORE, MARYLAND, ASSIGNOR OF ONE-HALF TO
FRANK J. HILBERT, OF SAME PLACE.

TRIPPING DEVICE FOR RAILWAY-SIGNALS.

SPECIFICATION forming part of Letters Patent No. 402,505, dated April 30, 1889.

Application filed January 22, 1889. Serial No. 297,224. (No model.)

To all whom it may concern:

Be it known that I, JOHN T. CARTER, of Baltimore, in the State of Maryland, have invented certain new and useful Improvements 5 in Tripping Devices for Railway-Signals; and I do hereby declare that the following is a full, clear, and exact description of the invention, which will enable others skilled in the art to which it appertains to make and 10 use the same, reference being had to the accompanying drawings, and to the letters of reference marked thereon, which form part of this specification.

My invention relates to an improved trip 15 or mechanism to be located upon a railroad-track beside a rail to be operated by the wheels of a passing car or train.

The object of the invention is to provide an improved trip or mechanism to be placed beside a railroad-rail and utilize the force and weight of the passing cars to operate danger and other signals, gates, &c.

The object is accomplished by, and my invention consists in, certain novel features of 25 construction and combinations of parts, more fully described hereinafter, and particularly pointed out in the claims.

Referring to the accompanying drawings, Figure 1 is a detached perspective view of the 30 trip. Fig. 2 is a side elevation of the various parts detached, the operating-levers being shown partially broken away.

In the drawings, the reference-letter *a* indicates a frog, base, or bed casting suitably secured—say to the sleepers—close to and extending along beside the inner side of a rail, and this supporting and protecting frog is preferably cast in one piece, and consists of the bottom horizontal flanges or pieces, *b b*, 35 leaving an opening between their inner ends, as shown, and having sockets *c c* at their outer ends open on their inner sides, and the outer side of the frog is closed or provided with an upwardly-extending side or flange, *d*, 40 extending throughout the longitudinal length of the same and extending upwardly from the bottom flanges a suitable distance, and the upper longitudinal edge of this side is sloped from the ends upwardly toward the center, 45 so that the vertical height of the side is greater at the center than at the ends. The opposite

side of the bed is open or has no side piece, but lies up against the rail, which protects the parts.

A pair of toggle links or levers, *e e*, are longitudinally located in the base, and are hinged or pivoted together, so that their adjoining pivoted ends will be located at the center of the base above the opening between the bottom plates, and these ends are normally on a 55 level with the middle of the top edge of the side flange, and from thence the links extend downwardly toward the opposite ends of the base, with their ends resting loosely upon the bottom flanges and extending into the sockets to allow longitudinal play. The ends of the links are slotted or bifurcated, as shown at *f*, and the sockets are provided with vertical rigid pins *g*, loosely extending through the slots to guide the links and movably hold 60 the same upon the bottom flanges, and the links are further loosely confined by pins *h*, secured to the same and extending loosely through the bottoms of the frog to limit the 65 upward movement of the levers.

In their normal position the hinged upper ends of the levers rest just beside the head of the rail, and are supported in this position by and bear directly upon the upper curved edge of a vertical bar or head, *i*, extending 70 up in the opening between the bottom flanges, and the head is loosely secured to the frog to allow vertical movement of the head by a longitudinal slot, *j*, in the same, and a nut and bolt or headed pin, *k*, secured to the frog and 75 extending loosely through the slot. The lower end of the head is extended downwardly, as shown, and pivoted to one arm of a bell-crank lever, *l*, pivoted at its elbow in a suitable box beneath the track to swing in a vertical plane, 80 and the opposite arm of the lever is connected with a signal or other device it is desired to operate. For instance, this device can be used to actuate the signal shown in my pending 85 application, Serial No. 290,283.

It is evident that when a train is passing the car-wheel flanges will depress the hinged ends of the levers and move the outer ends of the same into the sockets and depress the head, and consequently rock the bell-crank 90 lever and move the mechanism to be operated, and when the lever is swung in the opposite 95 100

direction the parts are returned to their normal position.

What I claim is—

1. A trip comprising a supporting and protecting frog adapted to be secured beside a railroad-rail and provided with an upwardly-extending flange on its outer side and horizontal bottom bearing-flanges, a pair of levers longitudinally located on said frog with their upper ends hinged together and their opposite free ends confined and movable on said bottom flanges, a head loosely secured to the frog to allow vertical movement and having a rounded upper end upon which the hinged ends of the levers rest, and an elbow-lever pivotally secured to the lower end of said head, substantially as described.

2. A trip comprising a supporting and protecting frog adapted to be secured beside a rail and provided with an upwardly-extending flange at its outer side and with bottom bearing-flanges, the ends of the frog having sockets open on their inner sides, a pair of levers longitudinally located on the frog hinged together at their upper adjoining ends and having their opposite ends loosely extending into said sockets, stops or guides for

said levers, and a head operated by the levers, substantially as described.

3. A trip comprising a frog adapted to be secured beside a rail and open on its inner side and top, one or more levers in the same adapted to be depressed by the wheels of a passing car, and a head upon which said lever or levers rest and adapted to be vertically moved by the same, said head having a vertical slot, and a headed pin secured to the frog and extending loosely through the slot, substantially as described.

4. A trip comprising a frog having bottom bearing-flanges and sockets, levers movably located in the frog with their ends in the sockets and bearing on the flanges, guiding-pins for the same, and a head upon which the levers rest loosely secured to the frog by a pin and slot, substantially as described.

In testimony that I claim the foregoing as my own I affix my signature in presence of two witnesses.

JOHN T. CARTER.
